WOOL DEGREASING MACHINE

Harry S. Drum, Abington, and Alfred Hopkins,
Philadelphia, Pa., assignors to Smith, Drum and
Company, Philadelphia, Pa., a corporation of
Pennsylvania

Application May 20, 1947, Serial No. 749,268

4 Claims. (Cl. 68—18)

1

The present invention relates to the treatment of raw wool and more particularly to an apparatus for removing grease, oil, and dirt, or other foreign substances from raw wool by use of solvents, one form of such an apparatus being shown in Patent No. 2,368,916, upon which the present invention is an improvement.

Some of the objects of the present invention are to provide an apparatus for removing oil, grease and dirt from raw wool; to provide an apparatus for conveying raw wool through a washing chamber while subjected to a solvent and thereafter through a heating chamber for recovering contained solvent; to provide a conveying means wherein provision is made for maintaining a uniform thickness of the wool while traversing the washing and heating chambers successively; to provide an apparatus which functions to prevent bunching of the wool while moving to thereby ensure uniform compactness and density; to provide means for reclaiming entrained solvent in the treated wool; to provide a degreasing apparatus wherein a novel balance of air pressure is maintained between the interior of the apparatus and the atmosphere; and to provide other improvements as will hereinafter appear.

In the accompanying drawings, Fig. 1 represents a side elevation, partly broken away, of a wool degreasing machine embodying one form of the present invention; Fig. 2 represents a sectional elevation of the drying chamber of the machine and illustrating the wool feed trough and mechanism as continued from the solvent chamber; Fig. 3 represents a section on line 3—3 of Fig. 2; Fig. 4 represents an enlarged detail showing the rake tine mounting and the wool trough and grille above the wool; Fig. 5 represents diagrammatically the air circulating system for reclaiming solvent; and Fig. 6 represents diagrammatically a control for maintaining air balance and also recovering otherwise waste solvent.

Referring to the drawings, one form of the present invention is shown as applied to a two unit degreasing apparatus comprising a casing 9 forming a washing chamber 10, and a drying chamber 11, the former being arranged to receive the wool to be treated at one end and deliver it at the other end to the drying chamber 11. The washing chamber 10 is arranged to subject the wool to the action of a degreasing solvent which, for example, can be supplied by spray nozzles 12 or other well known means. The drying chamber 11 is arranged to circulate heated

2

air through the wool and includes heating coils 13 arranged transversely of the chamber 11 to be supplied with steam or other heating medium from a suitable source. An air duct 14 communicates at its ends respectively with the top and bottom of the chamber 11 through which air is circulated by a fan unit in housing 15, driven by a motor 16.

For feeding wool to be treated successively through the chambers 10 and 11, the housing 9 for the respective chambers mounts a plurality of suitably spaced stringers 18 arranged in the same horizontal plane to serve as supports for a series of longitudinally disposed rails 20 to which an open top trough 21 is anchored. This trough 21 is of general U-shape and has a perforated bottom 22 to allow free passage of solvent in one chamber and circulation of air in the other chamber. The trough 21 extends as a continuous conduit through the two chambers 10 and 11, receiving the raw wool at one end and delivering the processed wool at the other end.

In order to feed the wool into the trough 21, various means can be employed, but the preferred construction is that of U. S. Patent No. 2,368,916, and generally comprise a hopper 23 suitably mounted exteriorly of the housing in position to discharge by gravity into a transverse passage 24 leading to and communicating with the receiving end of the trough 21. A push plunger 25 is arranged in horizontal alinement with the passage 24 for reciprocation through the side of the hopper 23 to propel the wool step by step into the trough 21. The plunger 25 is attached to a carriage 26 having rollers 27 riding on suitable side tracks 28, and receives motion by means of connecting rods 30, and cranks 31 rotated by suitable power transmitting means such as a belt, pulleys, and motor 32.

For causing the wool to travel through the trough 21, a plurality of rows of rake tines 33 are arranged transversely of the trough 21, each row being carried by a shaft 34 journaled for oscillation in ears 35 projecting from a cross-bar 36 which is attached at its ends to two carrier plates 37, these latter straddling the trough 21 and being supported on rollers 38 journaled respectively in the sides of the housing of the two chambers. Thus, the rows of tines are spaced longitudinally at effective distances to keep the wool mat properly in motion. Reciprocating motion is transmitted to the carrier plates 37 by a pair of drive rods 40 which receive motion from the plunger carriage 26. It should be noted that each shaft 34 carries two limit stop lugs 41 ar-

ranged to engage the adjacent cross-bar 36 so that the tines are held rigid on the working stroke but permit the tines to swing forwardly above the wool on the return stroke and thus avoid working the wool in the wrong direction.

For the purpose of preventing the wool from bunching or piling up as the tines push it forward, a grille is mounted to lie in a horizontal plane above the wool in the trough 21, this grille comprising a plurality of rigid, relatively thin bars 42 arranged in parallel relation, and so spaced laterally as to receive a rake tine 33 between each such pair of bars 42, said bars 42 being supported at suitably spaced intervals by cross rods 43. Flanged brackets 44 are welded or otherwise made fast to the respective sides of the trough 21, the brackets 44 at one side of the trough 21 being transversely alined with the respective brackets 44 at the opposite side of the trough 21. Each pair of these brackets 44 depends within the trough 21 the required distance to position the grille bars 42 in close proximity to the wool in the trough 21. One cross-rod 43 is attached at its ends between each pair of the brackets 44, and spacers 45 maintain the desired parallel relation of the bars 42. It will be understood that the aforesaid grille extends as a continuous unit throughout the length of the trough 21 parallel to and spaced a predetermined distance from the trough 21, so that the normal tendency of the wool to bunch upwards under the action of the tines is prevented by contact with the bars 42. By reason of this restraining action of the bars 42, the wool is also prevented from opening up through-holes which, unless prevented, would allow the solvent to bypass various areas of the wool and so result in non-uniform treatment.

As a means for reclaiming residual solvent contained in the wool, the discharge outlet 46 communicates with a casing 47 having a downwardly disposed arcuate conduit 48 leading to and discharging into a collecting receptacle 50. The inlet to the conduit 48 is at the level of the bottom of the outlet 46, so that the discharged wool can fall by gravity into the conduit 48. A baffle 51 is mounted within the casing 47 in spaced alined relation to the outlet 46 as an aid to directing the wool into the conduit 48. As a means to supplement gravity, a plunger 52 is carried, by a rock arm 53, in position to reciprocate towards and away from the entrance to the conduit 48 in order to function as a pusher propelling the wool towards the receptacle 50. The plunger 52 and the arm 53 are enclosed in the casing 47, while the shaft 54 to which the arm 53 is keyed projects outside of the casing for attachment of any suitable driving means (not shown). At a suitable location the conduit 48 is provided at opposite sides respectively with two alined perforated plates 55 and 56, the former opening into a chamber 57 formed by a housing 58, and the latter opening into a chamber 60 formed by a housing 61. The housing 57 has an inlet 62 forming the discharge end of a pipe 63 leading from the discharge end of a blower 64, whereby fresh air is forced through the wool between the plates 55 and 56. The housing 61 has an outlet 65 communicating with a pipe 66 which leads to the charging end of the machine where it discharges through a perforated plate 67 against the wool leaving the hopper 23. Thus, finally the solvent laden vapor about the wool leaving the drying chamber is absorbed by the circulating air and carried to

the charging end of the machine where it is discharged into the wool leaving the hopper. Thus, otherwise lost solvent in the solvent laden vapor is reclaimed and utilized.

5 The solvent reclaiming and air control system shown in Fig. 6 is shown alined with the discharge end of the machine and having the wool outlet conduit 46 extended to pass successively through an air duct 70 and then between a pair 10 of pressure rollers 71. These rolls 71 are located in a casing 72 and are driven from a suitable power means to rotate in the direction of wool travel. That portion of the conduit 46 within 15 the casing 72 is apertured at opposite sides to respectively allow the rolls 71 to ride into contact with the wool and produce a suitable squeezing of the fibers as a seal, so that the compressed wool at that location will prevent escape of solvent-collecting air to the wool exit 73 and to 20 maintain back pressure upon the entrained air. Escape of air about the periphery of the rolls 71 is blocked by joint sealing strips 74 and blocks 75, the latter being biased against the respective rollers by suitable compression springs 76. The 25 strips 74 and blocks 75 are preferably formed of rubber or like yielding material. That portion of the conduit 46 lying between the walls of the conduit 70 is perforated as shown at 77, so that a closed air circulating system picks up entrained 30 solvent and delivers it by the conduit 70 to the inlet of a circulator 78. The discharge from the circulator 78 is into the conduit 70 where a bypass pipe 80 carries off and delivers the solvent-laden air to a scrubber 81 having an outlet 82 35 for solvent free air and a return 83 for extracted solvent for delivery to the solvent tank. A damper valve 84 is located in the by-pass pipe 80 for manual or automatic control of the solvent-laden air. While this back pressure control unit 40 comprising the squeezing rollers 71 is here shown at the discharge end of the machine, a like unit may be provided to limit the amount of air drawn into the machine with the incoming wool, and thereby keep the entering air to a minimum, so 45 that the atmospheric pressure is in effect predominating at all times and solvent fumes prevented from escaping exterior of the machine.

As a means for maintaining a low air pressure within the machine, that is, preferably below 50 atmosphere, an air discharge pipe 85 leads from the chamber 11 to the conduit 70, entering the latter between the conduit 46 and the inlet side of the circulator 78. Thus, the pipe 85 is directly subjected to the suction of pipe 70 entirely independent of whether the wool squeezing unit is used as a part of the solvent reclaiming mechanism. A damper valve 86 in the pipe 85 serves as a control for maintaining effective air balance within the machine.

60 It will now be apparent that a complete unitary degreasing machine has been devised wherein loss of solvent has been reduced to a minimum and such a balance of air pressure relative to the atmosphere is maintained that the latter predominates so that solvent fumes are trapped 65 within the machine and cannot escape to the exterior thereof. Furthermore, by the use of the novel grid structure 42 the wool is kept at a uniform thickness throughout its travel through 70 the machine, and any tendency to bunch or pile up at one or more places is definitely impossible. In describing this grille 42 as being located at a predetermined distance from the trough, it is to be understood that such spacing is related to the 75 thickness of the wool web as well as the pressure

of the solvent spray, and for that purpose the grille is adjustable towards and away from the trough 21.

Having thus described our invention, we claim:

1. An apparatus for treating raw wool comprising a casing forming a solvent chamber and a drying chamber, said solvent chamber having a charging inlet and said drying chamber having a discharge outlet, means for feeding loose wool fibers in the form of a mat from said inlet to 10 said outlet, a conduit for conveying the discharged wool to a container, said conduit having a perforated inlet plate at one side and a perforated outlet plate at the opposite side, means for circulating fresh air through the wool from 15 said inlet plate to the outlet plate, and means for conveying the air from said outlet plate to the wool entering said charging inlet, whereby reclaimed solvent vapor is utilized.

2. An apparatus for treating raw wool comprising a casing forming a solvent chamber and a drying chamber, said solvent chamber having a charging inlet and said drying chamber having a discharge outlet, means for feeding loose wool fibers in the form of a mat from said inlet to 25 said outlet, a conduit for conveying the discharged wool to a container, said conduit having a perforated inlet plate at one side and a perforated outlet plate at the opposite side, a reciprocable plunger for feeding the discharged wool 30 through said conduit, means for circulating air through the wool from said inlet plate to the outlet plate, and means for conveying the air from said outlet plate to the wool entering said charging inlet, whereby reclaimed solvent is utilized.

3. An apparatus for treating raw wool, comprising a treating chamber having an inlet and an outlet in aligned relation, a trough having a perforated bottom longitudinally disposed in said 40 chamber in register with said inlet and said

outlet, a grille in said trough formed of a plurality of longitudinally disposed parallel spaced bars and extending substantially the length of said trough, means fixedly mounting said bars above and juxtaposed to wool on said trough, a plurality of rake tines for feeding wool along said trough between said grille and said perforated bottom, said tines passing respectively between said grille bars, and means to actuate said tines to feed loose wool fibres through said trough from said inlet to said outlet.

4. An apparatus for treating raw wool, comprising a casing forming a solvent chamber and a drying chamber, said solvent chamber having a charging inlet and said drying chamber having a discharge outlet, means for feeding loose wool fibers in the form of a mat from said inlet to 15 said outlet, means for circulating air in said casing through said mat to remove solvent therefrom, and means for passing fresh air through the discharged solvent free wool to remove the solvent laden vapor from about the wool.
